FOLDING MACHINE

Martin J. Bergen, West Newbury, Mass., assignor
to United Shoe Machinery Corporation, Paterson, N. J., a corporation of New Jersey

Application December 22, 1933, Serial No. 703,596

2 Claims. (Cl. 12—55)

This invention relates to folding the margin of pieces of sheet material which require the application of heat and to a heating device which may be used to apply radiant heat to selective 5 localities of shoe parts.

In the manufacture of boots and shoes, it is customary to fold certain margins of certain parts, for example the front and top margins of quarters and the rear margins of tips, in order 10 to produce finished edges thereon. Two procedures are in common use. In the first, the margin of the shoe part is skived, a coating of cement is applied to the margin, and then the margin is folded. In the other, a narrow binding strip carrying a coating of cement is sewed 15 along the edge of the shoe part, and then the strip is folded about the edge of said part. Thus in both cases the cement-coated margin of a piece of work is folded over upon the body portion thereof. In some instances, a cement is used which is normally not sticky but is adapted 20 to become sticky upon being heated.

The practice of employing a thermoplastic cement has been used principally on the latter of 25 the two kinds of work mentioned above, namely on so-called French binding, and various means have been employed to apply heat to the coating of cement, for example, directing upon the coating a blast of hot air as described in United 30 States Letters Patent No. 1,661,572, granted March 6, 1928, upon an application filed in the name of Clifford K. MacDonald, or providing a heated presser foot over which the coated binding is drawn, as disclosed in United States Letters 35 Patent No. 1,850,979, granted March 22, 1932, upon an application filed in the name of George E. Williamson.

In the illustrated construction, there is provided, in combination with a folding machine, a 40 device for heating the coating of cement on the margin of the work which comprises a source of radiant heat the rays of which are received upon one end of a conductor capable of delivering the rays from its other end, substantially 45 without loss, upon a selected portion of the work. Also as illustrated, this conductor is a fused quartz rod, which transmits the rays by internal reflection, the other end of said rod being located to deliver these rays upon the cement-coated 50 margin of the work prior to the folding over of the margin thereof. Owing to the fact that the fused quartz rod remains substantially cool and that it transmits the heat rays substantially without loss even though it may be curved to some 55 extent, the application of heat may be restricted

to the selected locality of the work without the presence near the work, in a position objectionable to the operator, of any hot member such as the nozzle of a hot air apparatus or the heated presser foot of a folding machine.

Referring to the accompanying drawing, Fig. 1 is a front elevation of a portion of a machine in which the present invention is embodied, and

Fig. 2 is an end elevation of parts of the machine showing a piece of work in process of being operated upon.

The folding machine and its mode of operation will be only briefly described. A piece of work, for example a piece of leather 100 to which a 15 strip of binding 200 is attached, is fed intermittently away from the observer, as viewed in Fig. 1, or to the left, as viewed in Fig. 2, over a work support 5, being held down upon the work support by a presser foot provided with a small roller 3. The margin of the work, in the illustrated case the binding strip, is bent up over the edge of the presser by a folding finger 11 to form the fold, said fold being then completed and pressed by a hammer 13 which grips the work and feeds 20 it intermittently. The folding machine herein shown is or may be substantially the same as the machine shown in Letters Patent of the United States No. 2,014,469, granted September 17, 1935, on an application filed in the name of John B. 25 Coffey, and will not be further described, since any suitable folding machine may be employed.

The binding strip has a coating of thermoplastic cement which may be softened and rendered sticky by being heated. For this purpose 30 there is provided a source of radiant heat in the form of a metallic helix 15 which forms part of an electric circuit, and a rod of fused quartz 17 arranged to receive heat rays from the source of heat and to deliver them to the work in advance 35 of the folding mechanism. The helix is carried as shown by a metallic reflector 19 to which is attached the larger end of a generally conical reflector 21, the upper end of the fused quartz rod 17 being mounted in a sleeve 23 which is clamped 40 to the small end of the reflector 21, both reflectors being covered by a layer of heat insulating material 25. This whole device is adjustably supported on an upright rod 27 carried by the upper arm 29 of the frame of the folding machine by 45 means of two horizontal rods 31, 33, the hubs of which are slidably and rotatably mounted on the upright rod, being held in adjusted positions respectively by thumb-screws 35, 37 which are 50 threaded through the hubs and engage the up- 55

right rod 27. At its outer end the lower rod 31 is pivoted at 39 to an ear 41 riveted to the reflector 21, the outer end of the upper rod 33 carrying a bracket 43 which is adjustably fastened, to an ear 45 riveted to the reflector 19, by a thumb-screw 47, the stem of which passes through a slot 49 in the bracket and is threaded into the ear. The heating device may thus be adjusted vertically about the vertical axis of the rod 27 when the screws 35, 37 have been loosened, and may be tilted about the axis of the pivot 39 after the thumb-screw 47 has been loosened. It is thus possible to locate the lower end of the fused quartz rod 17 in proper position with respect to the work. It should also be understood that the fused quartz rod may have curved portions if such curved portions are necessary or desirable in order to locate its lower end in proper position.

The work passes through the machine from right to left, as viewed in Fig. 2, the fused quartz rod delivering heat rays upon the coating of cement on the margin of the work as the work is fed, so that the coating is progressively rendered sticky and will cause the subsequently folded-over margin to adhere to the body portion of the work. The quartz rod transmits to the work the heat rays received upon its upper end and at the same time, since it remains substantially cool, interferes in no way with the manipulation of the work by the operator.

Although the invention has been described as used in the heating of a particular piece of work

during a particular operation, it should be understood that the invention is not limited in the scope of its application to use on the particular work nor to use with the particular machine which have been shown and described. 5

Having described my invention, what I claim as new and desire to secure by Letters Patent of the United States is:

1. A machine for folding a piece of flexible work having on its margin a coating of cement which is normally not sticky but may be rendered sticky by heat having, in combination, mechanism for feeding the work and for folding the margin, and means for heating the coating of cement, said last-named means comprising a source of radiant heat, and a member adapted to transmit heat rays by internal reflection having its delivery end adjacent to the coating of cement and its receiving end located in position to receive heat rays from the source of heat. 20

2. A machine for folding a piece of flexible work having on its margin a coating of cement which is normally not sticky but may be rendered sticky by heat having, in combination, mechanism for feeding the work and for folding the margin, and means for heating the coating of cement, said last-named means comprising a fused quartz rod having its delivery end located in position to direct radiant heat upon the coating of cement, and means for directing radiant heat upon the other end of the rod. 25 30
